GUN CARRIAGE

Thomas H. Sullivan, Salem, Mass., assignor to
 United Shoe Machinery Corporation, Flemington, N. J., a corporation of New Jersey

Application November 11, 1943, Serial No. 509,907

20 Claims. (Cl. 89—40)

1

This invention relates to carriages upon which such an article as a gun may be transferred from one point to another, it being especially adapted for the purpose of raising the gun-mount from the surface upon which it rests, supporting it upon wheels for its travel, and lowering it to a position in which it may be secured for firing.

It is an object of my invention to provide a carriage which may quickly be assembled with a gun-mount, which adds little in weight yet is amply strong, which requires the application of a relatively small force to elevate it from a lowered to a raised position upon its wheels, and which is generally convenient to manipulate. With this end in view, I combine with a carriage-body, which may be in the form of a spider having radiating arms, a mount for the gun to be transferred resting upon the body, together with wheeled supports for the rear and front of the body, and means respectively common to the rear and front supports, the body and the mount for securing these elements together. The mount thus becomes in effect a portion of the carriage, imparting strength and rigidity, and therefore requiring a comparatively light added body. Preferably, a rear wheel-assembly and a bracket for a forward wheeled truck are secured to the gun-mount and body, as by bolts furnishing the common connecting means preventing movement of the connected elements relatively to one another. As appears herein, the truck is pivoted between the forward bracket and an extension of one of the spider-arms. The center of the spider is shown as carrying securing means, which when the carriage is lowered engages a device relatively fixed, as in the deck of a vessel. To elevate the carriage for wheeling and to control its lowering for clamping, the carriage-body is provided with axles at the rear and front, there being wheels rotatable upon the axles. A toggle-lever connects the body to each of the axles, and there is means for straightening and breaking the toggles when the carriage is to be raised and lowered. These toggles greatly multiply the force applied, and operate smoothly with little wear. At the rear is shown a pair of connected axles upon which the wheels rotate, with a post rising from the connecting means at each axle. The carriage-body is guided upon these posts, and a hand-lever is fulcrumed upon the body and joined by the toggle-levers to the posts. The front truck may have spaced walls in which are guide-slots, and blocks are movable in these slots, an axle being free to turn in the blocks and the front wheel being rotatable about the axle. A

2

hand-lever fulcrumed upon the truck furnishes, with a link connected to the axle, the forward toggle-lever. Oscillation of the hand-levers outwardly and inwardly with respect to the gun-mount straightens or breaks the connected toggle-levers to lift the carriage upon the wheels for transfer of the gun, or allows it to descend for clamping to the deck. In their straightened relation, the toggle-levers may be retained for the travel of the carriage by means, as pivoted latches, engaging the hand-levers.

In the accompanying drawings,

Fig. 1 shows my improved carriage in side elevation and in firing position;

Fig. 2 is a rear elevation thereof;

Fig. 3, a top plan view;

Fig. 4, a view similar to Fig. 1, but with the carriage raised for towing; and

Fig. 5, a perspective view of separated portions of the rear wheel-assembly.

At 10 appears the standard of a mount for a gun, this standard being shown as in the form of a tripod, the legs of which rise from an annular base-ring 12. Attached to the lower face of the base is a spider 14, bolts 16 passing through each of its five arms near their outer extremities. This spider furnishes the body of a carriage for the gun-mount. The two rear arms 18, 18 of the spider diverge outwardly at equal angles to the center line of the carriage, and their bolts secure to the top of the base 12 a bar 20 of a rear wheel-assembly A. The front spider-arm 22 projects outwardly along the center line beyond the base-ring, while to said ring by the bolts of the adjacent spider-arms 24, 24 a forwardly and upwardly extending bracket 26 is secured. The bar 20 and the bracket 26, because of their fixed attachment to the spider, may be considered as portions of the carriage-body. In the bracket and in the spider-arm 22 are vertically aligned openings to receive the pintle 28 of a forward truck or limber B. Lugs 29, on the undersides of the arms 18, 18 near their ends and at a substantially equal distance from the center on the arm 22, supply a uniform three-point bearing when the spider supports the gun upon the deck.

Considering the rear assembly A, rising from each end of the bar 20, and welded to furnish therewith, in effect, an integral unit, is a bracket 30 (Fig. 5). At the top of each bracket, between divided portions, a horizontal pivot-pin 32 is rotatable. Secured to these pins, in the spaces in the brackets, are the ends of a generally U-shaped hand-lever 34, which may be swung from a point adjacent to the standard 10 outwardly and down-

wardly. To the outer end of each of the pins 32 an arm 36 is fixed, articulated to a link 38. The opposite extremity of each link is pivoted to a post 40 received in a vertical bore through a boss 42 upon the outer side of the bracket. The post has a reduced lower portion or stem 44, movable in a lower arm 46 of the bracket, there being between the post and the stem a shoulder 50. Surrounding each stem 44 is a block 48, the two blocks being joined by a rod 52. Each block has 10 projecting from its outer side a horizontal axle 54, about which is rotatable a wheel 56, and upon each block may rest the shoulder 50 of the corresponding post 40. Each of the arms 36 and links 38 furnishes a toggle-lever, through which movement of the hand-lever 34 may be transmitted to the body of the carriage and to the gun-mount.

When the hand-lever is swung in toward the gun-standard (Figs. 1, 2 and 3), the toggle-levers 36, 38 are broken outwardly, permitting the brackets 30 and the rear of the carriage to descend until the under face of the spider 14 rests upon the deck, or other supporting surface. To render the rear wheels 56 effective to support the gun-mount, the hand-lever 34 is drawn out until the elements 36 and 38 of each of the two toggle-levers are approximately alined with each other (Fig. 4). This causes the brackets 30 and the mount, to which they are attached, to be lifted along the posts 40, the weight of the parts being carried upon the wheels 56 through the toggle-levers and the contact of the shoulders 50 of the posts with the tops of the blocks 48. In this active relation, the hand-lever may be releasably retained by latches 58, 58. There is one of these latches for each of the arms of the lever 34, they being fast upon the opposite ends of a rod 60 rotatable in the brackets 30. A depression in the upper side of each latch receives a projection 62 from the lower end of each lever-arm. The latches are urged into engagement with the arms by expansion-springs 64 surrounding pins 66 pivoted to depending arms 68 of the latches, and guided in openings in the brackets. When the hand-lever is swung outwardly, the latches engage and retain it. When it is desired to reverse the movement of the lever and lower the mount, the depression of either latch will free both. The inner walls of the depressions, by engagement with the projections 62, limit the extent of outward movement of the lever 34.

The forward truck B has a body-portion consisting of a thick rear wall 76, from which project forwardly parallel side walls 78, 78. Through the wall 76 is a vertical bore to receive the pintle 28, which is carried in both the bracket 26 and the spider-arm 22. In the side walls are transversely alined vertical slots 80, 80, in each of which is a bearing-block 82, these receiving an axle 84 about which a wheel 86 is rotatable. The truck-body may thus rise and fall, guided by the blocks. Pivoted at 88 near the upper extremity of the walls 78 is the yoked extension 90 of a handle 92 for use in moving the carriage about the deck. That the handle may be more convenient for this purpose, it is preferably extensible, being tubular with a telescoping extension 94 provided with a hand-bar 96. A latch 98 movable in the upper end of the handle retains the extension in either its drawn-out or retracted relation, the latter being for the purpose described below.

In addition to its use in moving the carriage, the handle 92 serves to raise and lower the for-

ward end of the gun-carriage, as does the lever 34 the rear. The arms of the yoke 90 extend beyond the pivot 88 to furnish the upper links of double toggle-levers. The connected links 100, 100 of the toggle-levers are secured at their lower ends to the axle 84. The action of the handle 92, in lowering or raising the carriage, corresponds to that of the lever 34. With the handle swung inwardly toward the gun-standard (Figs. 1, 2 and 3), the toggle-levers 90, 100 are broken and the walls 78 of the truck-body slide down the blocks 82, until the forward portion of the under face of the spider rests upon the deck. When the handle is drawn outwardly to an extent permitted by contact of the arms of the yoke 90 with lugs 102, 102 upon the outer faces of the walls 78 (Fig. 4), the toggle-levers are so straightened that the forward portion of the carriage is elevated, its weight being borne by the toggle-levers and the axle 84. To secure the handle with the carriage raised, the lower end of each of the yoke-arms may be received in a depression in one of two latches 104, 104 fast upon the ends of a pivot-pin 106 turning in the truck-body. Each of the latches is urged up against the corresponding yoke-arm by an expansion-spring 108, interposed between it and a lug 110 upon the body. The handle may be freed for the lowering of the carriage by the depression of either latch.

If it is desired to mount a gun upon the carriage of this invention, it is only necessary to bolt to the underside of the base 12 of the gun-standard 10 a spider 14 with arms of appropriate lengths, simultaneously attaching to the base and spider by the same bolts the rear assembly A and the bracket 26 of the forward truck B. If the gun, thus mounted, is at rest, and it is to be transferred to another position for firing, the rear lever 34 and the forward handle and lever 92 will be found in toward the standard, with the respective toggle-levers 36, 38 and 90, 100 broken to allow the spider to rest upon the deck and support the mount. The handle-extension 94 lies within the body of the handle 92 to prevent interference with the standard. The levers 34 and 92 are successively swung out to straighten the toggle-levers. This greatly multiplies the force applied to lift the rear brackets 30 along the posts 40, and the forward truck-body 76, 78 along the blocks 82, causing the gun-mount to be supported, through the toggle-levers, upon the wheels 56 and 86. Here, it is retained by the latches 58 and 104. Now the handle 92, 94 may be extended so it is convenient for towing the carriage, which is thus drawn to the chosen point. Here, the levers are unlatched, shifted inwardly, so the toggle-levers are broken, and the mount permitted to descend until the spider again is supported upon the deck. To fix the gun in firing position, some such securing means as a screw 112 projects through an opening at the center of the spider and is adapted to engage a threaded socket 113, or other securing means, in the deck. This screw has a flange 114 for contact with the upper face of the spider, when said screw is turned down to secure the mount in place, and above the flange rises a stem 116 to receive a handwheel 118 for its rotation. The stem turns in the top of a casing 120 attached to the upper face of the spider. In its inactive position, during the shifting of the carriage, the screw is retained, raised within the casing, by a latch 122, pivoted at the bottom of the casing and urged into engagement with the flange 114 by an expansion-spring 124. An arm 126, projecting from

the latch outside the casing, may be depressed to release the screw for its entrance into the deck-socket.

It will be seen that the spider, with its spaced arms, provides a light carriage-body of ample strength, convenient for the reception of different mounts; and that the wheeled supports give a stable and readily maneuverable carrier for the body and the mounted gun, and lend themselves, without complication, to the introduction of the efficient toggle-levers. These multiply the applied force during the change in elevation of the carriage and permit such change to be effected speedily.

Having described my invention, what I claim as new and desire to secure by Letters Patent of the United States is:

1. In combination, a carriage-body, a gun-mount resting upon the body, a wheeled support for the rear of the body, a wheeled support for the front of the body, and means common to the body, the mount and respectively to the wheeled supports at the front and rear for securing these elements together.

2. In combination, a carriage-body, a gun-mount resting upon the body, a rear wheel-assembly, means for securing together the body, the mount and the assembly and being common to all these elements, a forward bracket, means for securing together the body, the mount and the bracket and being common to all these elements, and a truck connected to the bracket.

3. In combination, a carriage-body, a gun-mount having a base resting upon the body, a rear wheel-assembly resting upon the base, a forward bracket resting upon the base, bolts securing together the body, base, assembly and bracket, said bolts being so positioned and arranged as to prevent movement of the body, base, assembly and bracket relative to each other, and a truck pivoted upon the bracket.

4. In combination, a carriage-body, a gun-mount having a base resting upon the body, two spaced brackets and a connecting bar formed as an integral unit and resting upon the base, wheels rotatable upon the brackets, a forward bracket resting upon the base, bolts securing together the body, base, unit and forward bracket, said bolts being so positioned and arranged as to prevent movement of the body, base, unit and forward bracket relative to each other, and a truck pivoted upon the forward bracket.

5. In combination, a spider having radiating arms, a gun-mount having a base resting upon the arms near their outer extremities, one of said arms extending outwardly beyond the base, two rear brackets secured to the base and adjacent arms of the spider at the side thereof opposite the extended arm, wheels rotatable upon the brackets, a forward bracket secured to the base and to the spider-arms between the rear arms and the extended arm, and a truck pivoted between the forward bracket and the extended spider-arm.

6. In combination, a spider having radiating arms, a gun-mount having a base resting upon the arms near their outer extremities, one of said arms extending outwardly beyond the base, two rear brackets secured to the base and adjacent arms of the spider at the side thereof opposite the extended arm, wheels rotatable upon the brackets, a forward bracket secured to the base and to the spider-arms between the rear arms and the extended arm, a truck pivoted between the forward bracket and the extended spider-arm, and securing means carried at the center of the spider and

adapted for engagement with a relatively fixed device.

7. In a gun-carriage, a block, an axle projecting from the block, a wheel rotatable about the axle, a post rising from the block, a carriage-body upon which a gun may be supported for movement by the body between towing and firing positions, said body being guided upon the post, a hand-lever fulcrumed upon the body, and a toggle-lever joining the hand-lever to the post.

8. In a gun-carriage, a pair of axles, wheels rotatable about the axles, means for connecting the axles, a post for each axle rising from the connecting means, a carriage-body upon which a gun may be supported for movement by the body between towing and firing positions, said body being guided upon the posts, a hand-lever fulcrumed upon the body, and toggle-levers joining the hand-lever to both the posts.

9. In a gun-carriage, a block, an axle projecting from the block, a wheel rotatable about the axle, a post rising from the block, a carriage-body upon which a gun may be supported for movement by the body between towing and firing positions, said body being guided upon the post, a hand-lever fulcrumed upon the body, a toggle-lever joining the hand-lever to the post, and a latch pivoted to the body and engaging the hand-lever.

10. In a gun-carriage, a carriage-body upon which a gun may be supported for movement by the body between towing and firing positions, spaced brackets rising above the body and each provided with a guide-opening, a post received in each opening, a block by which each post is supported, connecting means between the blocks, an axle projecting from each block, a wheel rotatable upon each axle, and means for raising and lowering the brackets along the posts.

11. In a gun-carriage, a carriage-body upon which a gun may be supported for movement by the body between towing and firing positions, spaced brackets rising above the body and each provided with a guide-opening, a post received in each opening, a block by which each post is supported, connecting means between the blocks, an axle projecting from each block, a wheel rotatable upon each axle, a hand-lever fulcrumed upon the brackets, and toggle-levers joining the hand-lever to the posts.

12. In a gun-carriage, a carriage-body upon which a gun may be supported for movement by the body between towing and firing positions, spaced brackets rising above the body and each provided with a guide-opening, a post received in each opening, a block by which each post is supported, connecting means between the blocks, an axle projecting from each block, a wheel rotatable upon each axle, a hand-lever fulcrumed upon the brackets, toggle-levers joining the hand-lever to the posts, and a latch pivoted upon each bracket for engagement with the hand-lever.

13. In a gun-carriage, a carriage-body upon which a gun may be supported for movement by the body between towing and firing positions, a truck pivoted to the body and provided with spaced walls in which are guide-slots, blocks movable in the slots, an axle free to turn in the blocks, a wheel rotatable about the axle, a hand-lever fulcrumed upon the truck, and a link joining the hand-lever to the axle.

14. In a gun-carriage, a carriage-body upon which a gun may be supported for movement by the body between towing and firing positions, a truck pivoted to the body and provided with spaced walls in which are guide-slots, blocks mov-

able in the slots, an axle free to turn in the blocks, a wheel rotatable about the axle, a hand-lever fulcrumed upon the truck, a link joining the hand-lever to the axle, and means for temporarily retaining the hand-lever in a position outward from the carriage.

15. In a gun-carriage, a carriage-body upon which a gun may be supported for movement by the body between towing and firing positions, a truck pivoted to the body and provided with spaced walls in which are guide-slots, blocks movable in the slots, an axle free to turn in the blocks, a wheel rotatable about the axle, a hand-lever fulcrumed upon the truck and having an extension, and a link joining the lever-extension to the axle 15 and furnishing therewith a toggle-lever.

16. In a gun-carriage, a carriage-body upon which a gun may be supported for movement by the body between towing and firing positions, a truck pivoted to the body and provided with spaced walls in which are guide-slots, blocks movable in the slots, an axle free to turn in the blocks, a wheel rotatable about the axle, a hand-lever fulcrumed upon the truck and having an extension, a link joining the lever-extension to the axle 20 and furnishing therewith a toggle-lever, and a latch pivoted upon the truck and engaging the hand-lever.

17. In a gun-carriage, a carriage-body upon which a gun may be supported for movement by the body between towing and firing positions, a truck pivoted to the body and provided with spaced walls in which are guide-slots, blocks movable in the slots, an axle free to turn in the blocks, a wheel rotatable between the walls about the axle, a hand-lever fulcrumed upon the truck and having a yoked extension, and links joining the arms of the yoke to the opposite extremities of the axle.

18. In a gun-carriage, a carriage-body upon which a gun may be supported for movement by the body between towing and firing positions, a

truck pivoted to the body and provided with spaced walls in which are guide-slots, blocks movable in the slots, an axle free to turn in the blocks, a wheel rotatable between the walls about the axle, a hand-lever fulcrumed upon the truck and having a yoked extension, links joining the arms of the yoke to the opposite extremities of the axle, and latches pivoted upon the truck and engaging the ends of the yoke-arms.

19. In a gun-carriage, a pair of rear axles, wheels rotatable about the axles, means for connecting the axles, a post for each axle rising from the connecting means, a carriage-body upon which a gun may be supported for movement by the body between towing and firing positions, said body being guided upon the posts, a hand-lever fulcrumed upon the body, toggle-levers joining the hand-lever to both the posts, a truck pivoted to the front of the body and provided with spaced walls in which are guide-slots, blocks movable in the slots, an axle free to turn in the blocks, a wheel rotatable about the axle, a hand-lever fulcrumed upon the truck, and a link joining the hand-lever to the axle.

20. In a gun-carriage, a pair of rear axles, wheels rotatable about the axles, means for connecting the axles, a post for each axle rising from the connecting means, a carriage-body upon which a gun may be supported for movement by the body between towing and firing positions, said body being guided upon the posts, a hand-lever fulcrumed upon the body, toggle-levers joining the hand-lever to both the posts, a latch pivoted upon the body and engaging the hand-lever, a truck pivoted to the front of the body and provided with spaced walls in which are guide-slots, blocks movable in the slots, an axle free to turn in the blocks, a wheel rotatable about the axle, a hand-lever fulcrumed upon the truck, a latch pivoted upon the truck and engaging said hand-lever, and a link joining the hand-lever to the axle.

THOMAS H. SULLIVAN.
